(57) **CLAIM**

The ornamental design for a floor mop, as shown and described.

DESCRIPTION

FIG. 1 is a perspective view of a design for a floor mop; FIG. 2 is a top view thereof; FIG. 3 is a left side view thereof, the right side view being a mirror image thereof; FIG. 4 is a bottom view thereof; FIG. 5 is a front view thereof; and, FIG. 6 is a rear view thereof.

The broken lines shown in the drawings are for illustrative purposes only and form no part of the claimed design.
